[57] **CLAIM**

The ornamental design for a beverage container, as shown and described.

DESCRIPTION

FIG. 1 is a top right front perspective view of a beverage container showing our new design;

FIG. 2 is a front elevational view thereof;

FIG. 3 is a right side elevational view thereof; the left side elevational view being a mirror image;

FIG. 4 is a rear elevational view thereof;

FIG. 5 is a top plan view thereof;

FIG. 6 is a bottom plan view thereof;

FIG. 7 is a top right front perspective view of the subject invention, shown with the environmental unclaimed features removed;

FIG. 8 is a front elevational view of the subject invention, shown with the environmental unclaimed features removed; FIG. 9 is a right side elevational view of the subject invention, shown with the environmental unclaimed features removed; the left side elevational view being a mirror image;

FIG. 10 is a rear elevational view of the subject invention, shown with the environmental unclaimed features removed;

FIG. 11 is a top plan view of the subject invention, shown with the environmental unclaimed features removed; and,

FIG. 12 is a bottom plan view of the subject invention, shown with the environmental unclaimed features removed.

The broken line showing of a lid and handle in FIGS. 1 through 6 is for illustrative purposes only and forms no part of the claimed design.
